Primary Examiner — Stacia Cadmus(74) Attorney, Agent, or Firm — Crowell & Moring LLP(57) CLAIM

The ornamental design for a wheel or wheel cover, as shown and described.

DESCRIPTION

FIG. 1 is a front view of a wheel or wheel cover according to our design; and,

FIG. 2 is a perspective view thereof.

The broken line showing of the rear of the wheel and the bolt holes and center opening in the central hub area is included for the purpose of illustrating environment and forms no part of the claimed design.
